(57) **CLAIM**

The ornamental design for a solid food, as shown and described.

DESCRIPTION

FIG. 1 is a front, bottom and right side perspective view of a solid food;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof;

FIG. 7 is a right side elevation view thereof; and,

FIG. 8 is a cross-sectional view thereof, taken along line 8-8 in FIG. 2.

The evenly-spaced broken lines in FIGS. 1-8 illustrate portions of the solid food that form no part of the claimed design. The dash-dot broken lines in FIGS. 1 and 2 illustrate the boundary of the claimed design which forms no part thereof.

1 Claim, 8 Drawing Sheets
